VAPORIZER IN ATMOSPHERE OF ELECTRICALLY CHARGED GAS

Edgar R. Gould, Brookline, Mass.

Application June 26, 1934, Serial No. 732,464

3 Claims. (Cl. 261—73)

The present invention relates to apparatus for causing an electrically charged gaseous current such as air to act upon a vaporizable oil through surface contact therewith.

5 The purpose and object of the invention is to improve and reorganize the means for causing intimate contact between the charged gas and vaporizable liquid for the purpose of promoting a more intimate contact and insuring that an 10 accurate and predetermined level of the liquid shall be maintained at a proper height determined by the requirements of operation.

With this and other objects in view, the various features of the invention consist in certain 15 novel features of construction, combinations and arrangements of parts hereinafter described and claimed, the advantages of which will be obvious to those skilled in the art from the following description.

20 In the accompanying drawing illustrating the preferred form of the invention, Fig. 1 represents a side elevation of my improved vaporizer with a supply tank or reservoir connected thereto; Fig. 2 is a plan view of the pan disassembled from the remainder of the vaporizer; Fig. 3 is a bottom plan view of the cover portion removed from the pan; and Fig. 4 is a section in elevation of the cover and pan in assembled relation, taken generally on the line 4—4 of Fig. 3.

25 It will be understood by those skilled in the art that the present invention is concerned with the problem of maintaining an intimate contact between an electrically charged body of air and an oil such as pine oil to be vaporized by such contact. To secure the maximum effectiveness of the apparatus the oil should be maintained in a thin film in contact with the charged gas passing thereover, and should be continuously replenished in small and relatively constant increments to 30 avoid the formation of stagnant portions of oil which tend to scum or cook and prevent the desired operation, namely, the vaporization of the oil in the form of a fine mist readily disseminated throughout the charged air current and delivered 35 from the apparatus in this form. If a constantly supplied body of oil at the proper level is not maintained, the operation becomes intermittent and non-uniform, the supply tending to block off and cease feeding, and then suddenly meeting the demand for oil by feeding a surplus quantity 40 which causes a like intermittent operation in the formation of the vapor. The apparatus, unlike the ordinary type of gravity feed liquid level reservoir, involves problems due to the character 45 of the oil employed, the necessity for an accurate 50

and determinable level to maintain the requisite thin film, and the requirement for relatively continuous constant feed to avoid even the slightest variation in this film. The apparatus in addition avoids intermixture and possible contamination 5 of the vaporizable liquid in the supply reservoir by charged air or gas through the employment of a separate feed chamber sealed from the gas space and constantly replenishing the oil film from beneath without allowing substantial entrance of gas into the feed chamber or the reservoir communicating therewith. The feed chamber is vented directly to atmosphere, further promoting a constant feed and making the feed independent of variations in the pressure which may 10 be present in the gas chamber.

55 Referring more particularly to the illustrated embodiment of the invention, the vaporizer proper comprises a liquid pan 10 having a relatively smooth bottom portion 12 provided with a circular depression 14 communicating with longitudinal feed grooves 16. The pan is provided with a removable cover 18 resting upon the rim 20 of the cover, and generally sealing the space provided thereby. The removable cover is provided 25 with a gas inlet 22 and generally tangential outlet 24. Electrically charged gas in the form of air is conducted to the inlet 22 under sufficient pressure to cause the gas to traverse through the vaporizer and outlet 24. During its traverse 30 the gas is caused to pursue a tortuous path over the surface of the oil by partitions or baffle members 26 and 28, and the sealed partition 30, the path of the gas being indicated generally in dot and dash lines. The partition 30, as indicated 35 more particularly in Fig. 4, is flush with the rim 20 at its lower or meeting edge, and contacts with the bottom 12 of the pan to seal the feed chamber 32 from the gas chamber surrounding it. The fresh oil to be vaporized is delivered to the chamber 32 and flows thence into the surrounding gas chamber through the central depression 14 and the communicating groove 16, as shown more particularly in Fig. 4. By proper maintenance of the oil level slightly above the level of the flat 40 bottom 12, a thin film of oil is caused to spread over the entire bottom for intimate contact with the charged gas. The maintenance of this level and its constant replenishment is of the utmost importance in this type of apparatus. 50

The oil is normally delivered to the feed chamber 32 by gravity, this being accomplished through an inverted reservoir in the form of a bottle 35, which may be threaded at its neck into an internally threaded nipple 36. This nipple or fit- 55

ting is provided with a threaded stem 38 which is adjustably mounted at 40 in the wall of the cover above the feed chamber. The nipple and stem are provided with a passage of substantial cross-section 42 for the delivery of oil. This passage is closed at its lower end except for the provision of an inclined opening 44 formed by slabbing off the lower edge to produce the segmental opening 44 shown in Figs. 3 and 4. In addition, the lower face 48 of the feed stem is formed with a slight projection 50, which aids materially in the continuous supply of the requisite small quantities of oil, probably due to the fact that the projection formed at the edge of the opening produces in effect a miniature spout which promotes delivery of the oil in the form of small and finely divided droplets.

In operation, after filling the reservoir the stem is threaded into the cover until the bottom of the delivery spout contacts with the adjacent region of the pan. Thereafter the stem is backed off until approximately located in the position shown in Fig. 4 suitable for the maintenance of the oil level. It will be evident that with the oil maintained at a height to produce a thin film over the bottom 12 of the pan, the delivery chamber 32 will be completely sealed from the surrounding space by the curved and continuous partition 30, the lower edge of which contacts with the bottom of the pan and is sealed by the liquid. New oil delivered to the chamber may flow outwardly through the longitudinal grooves and replenish the film, but the space within the chamber is prevented from contamination through the surrounding gas space.

The interior of the chamber is constantly maintained at atmospheric pressure through the provision of a vent 52 formed in the cover, as indicated in Fig. 3, and causing the interior of the feed chamber to communicate with atmosphere at one side of the stem.

It is important in this type of apparatus that the electrically charged air or gas be maintained in this state and prevented from losing its positive or negative charge. To this end it may be desirable to provide the interior of the gas chamber with means encountered by the gas and charged similarly to the gas to cause maintenance

of the proper conditions. These means may take the form of bars 54 located within the gas chamber adjacent the inlet and outlet and intermediate thereof, these bars forming a part of the vaporizer proper, the entire assembly being maintained under a charge similar to that imposed upon the gas by a lead 60 connected to a terminal 62. Obviously the charge means contacting with the gas may be in other suitable form which will tend to maintain the charge without interfering with the conduction of the gas through the chamber and its contact with the liquid.

What is claimed is:

1. Apparatus for promoting contact between an electrically charged gas and a vaporizable liquid comprising a gas and liquid contact chamber, a feed chamber, a detachable supply member for replenishing the feed chamber by gravity, a hollow stem closed at its bottom portion and venting through an opening formed in the side and bottom, the edge of the opening at the bottom being depressed to promote delivery of small quantities of liquid.

2. Apparatus for promoting contact between an electrically charged gas and a vaporizable liquid comprising a pan having a flat bottom for the formation of a liquid film with feed grooves formed in the bottom for supplying the film, a cover assembled with the pan and forming in conjunction therewith a closed contact chamber, a sealing partition for providing a separate feed chamber, a supply fitting threadedly engaged with the cover above the feed chamber, a liquid reservoir connected to the supply, and means for venting the feed chamber to atmosphere.

3. Apparatus for promoting contact between an electrically charged gas and a vaporizable liquid comprising a vaporizer housing enclosing a gas and liquid contact chamber, means for maintaining a film of liquid within the chamber, means for causing contact between the gas and liquid, means located in the gas space above the liquid designed to maintain an electric charge, and a connection for imposing a charge of the desired polarity upon the vaporizer housing and connected means.
